(57) **CLAIM**

The ornamental design for an chair, as shown and described.

DESCRIPTION

FIG. 1 is a front and left side perspective view of a first embodiment of a chair showing my new design;

FIG. 2 is a right side elevational view thereof;

FIG. 3 is a rear elevational view thereof;

FIG. 4 is a front and left side perspective view of a second embodiment of my new design showing a different chair leg material;

FIG. 5 is a right side elevational view of a second embodiment of the chair in FIG. 4;

FIG. 6 is a rear perspective view thereof;

FIG. 7 is a front and left side perspective view of a third embodiment of the chair in FIG. 4 showing a lighter seat shell;

FIG. 8 is a right side elevational view of a third embodiment of the chair in FIG. 7;

FIG. 9 is a rear elevational view thereof;

FIG. 10 is a front and left side perspective view of a fourth embodiment of the chair in FIG. 1 showing a lighter seat shell;

FIG. 11 is a right side elevational view of a fourth embodiment of the chair in FIG. 10;

FIG. 12 is a rear elevational view thereof;

FIG. 13 is a front and left side perspective view of a fifth embodiment of the chair in FIG. 4 showing a hook on the left side of the legs next to the seat shell;

FIG. 14 is a front and left side perspective view of a sixth embodiment of the chair in FIG. 4 showing an indicia of seat numbers on the left side of the seat shell;

FIG. 15 is a partial front and left side perspective view of a sixth embodiment of the chair in FIG. 14;

FIG. 16 is a front and left side perspective view of a seventh embodiment of the chair in FIG. 14 showing a lighter seat shell; and,

FIG. 17 is a partial front and left side perspective view of a seventh embodiment of the chair in FIG. 16.

The broken line showing of a seat number in FIGS. 14-17 is for illustrative purposes only and forms no part of the claimed design.
